UNITED STATES PATENT OFFICE.

RODOLPHE W. E. CHRISTESEN, OF NEW BRITAIN, CONNECTICUT, ASSIGNOR
TO THE RUSSELL & ERWIN MANUFACTURING COMPANY, OF SAME PLACE.

DESIGN FOR A LATCH-CASE.

SPECIFICATION forming part of Design No. 19,129, dated June 4, 1889.

Application filed April 1, 1889. Serial No. 305,606. Term of patent 14 years.

To all whom it may concern:

Be it known that I, RODOLPHE W. E. CHRISTESEN, a citizen of the United States, residing at New Britain, in the county of Hartford and State of Connecticut, have invented and produced a new and original Design for a Latch-Case, of which the following is a specification, reference being had to the accompanying drawings, forming part thereof.

10 Figure 1 shows in elevation one of the broad sides of my newly-designed latch-case, and Fig. 2 a transverse section on line α α of Fig. 1 of the plates on opposite sides of the case.

15 The leading feature of my design consists in the raised beads extending vertically along each edge of the plate and at a point between the vertical edges.

20 A A designate the plates on the opposite sides of the case, the contour of which plates, as viewed in Fig. 1, being a four-sided figure with straight and parallel vertical edges, while the top and bottom edges are uneven, as shown.

25 3 3 designate raised beads at the vertical edges, and 4 4 a pair of vertical beads between said edges. The contour at the upper and lower edges slants inwardly in a straight line from each of the beads 3 3 to a point near the

30 pair of intermediate beads 4 4 and then outwardly to a point near the ends of said beads

4 4, forming three projections 5 5 5, the summit or most prominent points of which are substantially in one horizontal plane at the upper and lower edges of the latch-plates, 35 thereby giving a pleasing effect in connection with the vertical beads. Between the pair of beads 4 4 and the bead 3 at the front edge of the plates I form a series of transverse beads, as shown. The remaining portion of each 40 plate may be plain or ornamented to a greater or less extent, as may be desired—as, for instance, by the circular bead 7.

What I claim is—

1. The design for a latch-case herein shown 45 and described, the same comprising the vertical edge beads 3 3, intermediate pair of vertical beads 4 4, and series of transverse beads 6, the contour of the plate at the top and bottom edges being uneven, with points 5 5 5 projecting from said vertical beads.

2. In a design for a latch-case herein shown and described, the case having contour composed of parallel side edges and uneven top and bottom edges forming the points 5 5 5, 55 the face of the case having the vertical edge beads 3 3, and intermediate pair of vertical beads extending to said points.

RODOLPHE W. E. CHRISTESEN.
